WASTE RECEPTACLE

Joseph H. Solomon, Columbia, Pa.

Application January 14, 1946, Serial No. 641,061

3 Claims. (Cl. 220—87)

1

This invention relates to waste receptacles of the general type in which an inner can is nested within an outer enclosing can and a treadle is provided for simultaneously lifting a lid and raising the inner can above the level of the outer can.

An important object of my invention is to provide in a waste receptacle of the above character means operable upon raising the lid for automatically discharging a fluid chemical, such as a disinfectant, deodorant, perfume or scent, into the inner can, which may contain garbage, trash or other refuse, so as to maintain a sanitary condition and to avoid objectionable odors. In the preferred form of my invention the chemical is discharged from a supply container into the inner can during the interval the lid remains raised so as to be thoroughly intermingled with the refuse as it is deposited in the receptacle.

Another object of my invention is to provide in a waste receptacle of the above character, means for setting a sounding device, such as a music box, in operation upon lifting the lid of the receptacle and for discontinuing such operation upon closing the lid. The sounding device thus not only serves the useful function of calling attention to the fact that the lid is not completely closed, allowing the escape of odors from the receptacle and causing the wasteful discharge of chemical from the supply container, but the receptacle, including the music box, constitutes an unusual kitchen novelty.

Still another object of my invention is to provide in a waste receptacle of the above character improved treadle-operated means for simultaneously lifting the lid and projecting the inner can upwardly.

A further object of my invention is to provide a waste receptacle of simple and economical construction and which is effective in operation.

Other objects and advantages will be apparent from the following detailed description of a preferred embodiment of the invention, reference being had to the annexed drawing in which:

Figure 1 is a view of a waste receptacle in vertical cross-section, showing the inner and outer cans thereof;

Figure 2 is a transverse cross-sectional view of the waste receptacle taken on the line 2—2 of Fig. 1;

Figure 3 is a detail cross-sectional view showing the manner in which the treadle for raising the lid of the receptacle is mounted in the wall of the outer can; and

Figure 4 is a perspective view, with parts broken away for greater clearness, of the chemical sup-

2

ply container, showing the mounting of the valve for releasing fluid therefrom.

In Fig. 1 of the drawing is illustrated in vertical cross-section a waste receptacle suitable for kitchen use comprising a cylindrical inner can 1 intended for the reception of garbage enclosed within a cylindrical outer can 2 of slightly larger diameter, both cans being made of sheet metal or other suitable material and having closed bottoms and open tops. A lid 3 having a hinged connection 4 with the rim of the outer can is adapted to swing into and out of closed position relative to the top of this can.

For swinging the lid to open position there is provided a treadle 5 located externally of the outer can and connecting the two ends of an operating rod 6. The operating rod is intermediate looped as shown in Fig. 2 and covered with rubber tubing 7 which engages the bottom of the inner can 1, and the two ends of the rod project through oversize openings in the wall of the outer can 2 adjacent its lower end. The openings through which the ends of the rod 6 pass are each closed by a bushing 8 (Fig. 3) made of resilient material, such as soft rubber. By depressing the treadle, the bushings flex sufficiently to allow the rod to assume the inclined position of Fig. 1 with its looped portion pushing against the bottom of the inner can 1 to project the top of this can above the top of the enclosing can 2.

The operating rod 7, exterior of the outer can 2, is connected by a link 9 to a lever 10 projecting from one side of the lid. Thus, by depressing the treadle, the link acts to rock the lid to open position while at the same time the looped intermediate portion of the operating rod projects the inner can upwardly as illustrated in Fig. 1.

For maintaining a sanitary condition of the waste receptacle or for counteracting bad odors that may emanate therefrom, there is supported against the wall inside and adjacent the top of the inner can, as by means of hooks 11a, a supply container 11 for a fluid chemical such as a disinfectant, deodorant, scent or perfume.

As best shown in Fig. 4, the supply container is of box shape and is longitudinally divided by a partition 12 into a chemical storage chamber 13 and a distributing chamber 14. The partition adjacent its lower end is formed with a series of small ports 15 furnishing communication between the two chambers. A gate valve comprising a shutter 16 is mounted in face-to-face sliding contact with the partition 12 by means of inturned guide flanges 12a extending along the vertical sides of the partition. A stem 17 is connected at

its lower end with the shutter and has its upper end projecting upwardly through an opening in the supply container. A coil spring 18 encircling the projecting end of the stem exerts a thrust between a head 17a on the stem and the top of the container so as normally to hold the shutter in raised position uncovering the ports 15. The stem 17 is so located relative to the plane of the rim of the outer can 2 that when the lid 3 is closed it strikes the head 17a of the stem and, by means of its weight, holds the shutter 16 depressed against the action of spring 18 shutting off the ports 15.

A hollow tube 19 bent to circular shape lies partly within a depression formed upon the inner surface of the inner can 1 and has its two ends secured in openings 20 in the bottom of the distributing chamber 14. Chemical flows out of the distributing chamber into the tube 19 and is discharged onto the contents of the inner can through vents 21 formed in the wall of the tube throughout its length.

Mounted in the bottom of the outer can 2 is a spring-motor actuated music box 22 having a control lever 23 connected by a link 24 to the operating rod 6. The arrangement is such that when the treadle 5 is at rest the position of the control lever is such as to maintain the music box silent, but when the treadle is depressed the link 24 is pulled upwardly to shift the control lever to start the music box playing. When, for any reason the lid 3 does not tightly close upon the outer container—as, for example, by reason of an obstruction under the lid or because of the accidental resting of some object against the treadle 5—the continued playing of the music box will announce this fact so that the condition may be corrected and the escape of odors and the waste of chemical can be avoided. A key 25 associated with the music box extends through the wall of the outer can for convenience in winding the spring motor as occasion requires.

It will be apparent from the foregoing description that the waste receptacle of my invention is sanitary, attractive and effective in operation besides constituting a useful kitchen novelty. While I prefer to use a music box in the preferred construction of my invention, this may be omitted if desired, or other sound-producing devices may be substituted therefor.

While a preferred specific embodiment of the invention has been set forth, it is to be understood that the invention is not limited to the exact constructions illustrated and described, because various modifications of these details may be made within the purview of the appended claims.

I claim:

1. A waste receptacle comprising an outer can, an inner can enclosed by and slidable within the outer can, a common lid for the open upper ends of said cans, a hinged connection of the lid to the outer can to permit swinging of the lid to open and closed positions with respect to the cans, a lever secured to the lid and disposed in a plane transverse to the axis of the hinged connection, an operating rod for said lid extending through an opening in the wall of the outer can adjacent its lower end, a resilient bushing mounted in the opening, encircling the rod and sealing the opening in said wall, said rod being solely longitudinally rockingly supported within the bushing and

having its inner end located below the bottom of the inner can and having its outer end formed to provide a treadle and a link extending between and pivotally connected to the rod and said lever, whereby depression of the treadle causes simultaneous opening of the lid and upward projection of the inner can.

2. A waste receptacle comprising a can for the reception of waste material, a lid swingable to open and closed positions relative to said can, a container for a chemical supported within said can, a valve for releasing chemical from said container into said can, said valve being operably associated with the lid so as to be opened when the lid is raised and being moved to closed position when the lid is lowered, a rod operatively connected to said lid for swinging the lid to open position, a sounding mechanism positioned within the can and being continuously operable only when the lid is open, a control member for initiating and arresting the operation of said sounding mechanism and means extending between said rod and control member for actuating said control member to arrest the operation of the sounding mechanism upon closing of the lid.

3. A waste receptacle comprising an outer can, an inner can enclosed by and slidable within the outer can, a common lid for the open upper ends of said cans, said lid being swingable to open and closed positions relative to said cans, a lever secured to the lid and disposed in a plane transverse to the axis of the hinged connection a container for a chemical supported within the inner can, a valve operable upon opening of the lid for releasing chemical from said container into said inner can, an operating rod for said lid extending through an opening in the wall of the outer can adjacent its lower end, a resilient bushing mounted in the opening, encircling the rod and sealing the opening in said wall, said rod being solely longitudinally rockingly supported within the bushing and having its inner end located below the bottom of the inner can and having its outer end formed to provide a treadle, a link extending between and pivotally connected to the rod and said lever, whereby depression of the treadle causes simultaneous opening of the lid and upward projection of the inner can, a music box positioned within the outer can below the inner can and continuously operating only when the lid is open, a control member for initiating and arresting the operation of said music box and means extending between and connecting said treadle rod and control member for actuating said control member to arrest the operation of the music box upon closing of the lid.
